CAR COUPLER

Edmund P. Kinne, Alliance, Ohio, assignor to
American Steel Foundries, Chicago, Ill., a corporation of New Jersey

Application January 26, 1942, Serial No. 428,179

30 Claims. (Cl. 213—109)

My invention relates to railway car couplers of the so-called automatic knuckle type and, particularly, to a relatively recent design designated tight lock, a form of which has been made a present standard by the Association of American Railroads.

In the present A. A. R. standard tight lock coupler, the contour surfaces of the knuckles and coupler heads are machined in order to get a very close mating with a minimum of clearance or free slack therebetween. In couplers of this type, there is no provision for vertical and horizontal angling of one coupler relative to another, and mated couplers are secured in locked position by wedge-type locks designed to cooperate with wedge faces on the knuckles and, by a gravity action, operate to compensate for wear or adjustments occurring due to the seating of the surfaces of the various parts against each other, said wedge feature being designed to maintain all parts in a tight condition and prevent play between the mated or locked couplers. It will readily be understood that the production or manufacture of a coupler of the tight lock type above referred to will necessitate accurate production of parts and the machined surfaces must be close fitting to obtain the tight condition and, at the same time, must admit of interchangeability of all parts which is a prime requisite of any coupler utilized on American railways.

Under service conditions, it has been found that because of the wedge design of the locks and their wedge engagement with the abutting knuckle surfaces, the locks have a tendency to creep upward under the pulling force exerted on the couplers and, as a result, to cause accidental uncoupling unless the upward creeping movement is limited or stopped by a lock-to-the-lock, sometimes known as an anticreep device. In other words, the safety of such a coupler utilizing a wedge-type lock must depend upon the efficient functioning of the anticreep device associated therewith.

Another difficulty with such wedge-type locks as have been utilized and are at present being utilized in the standard tight lock coupler arises from the fact that the wedge surfaces on the lock and the adjacent knuckle sometimes become so tightly wedged against each other, with the lock between the knuckle and the vertical locking wall of the coupler head, that it becomes difficult and sometimes impossible to manually operate the lock to unlock the coupler. This condition may also arise when it is desired to open the knuckle of a coupler in order to lock it with

a mating coupler if, for any reason, the knuckle of the coupler has been closed to locked position. Moreover, because of the fact that the couplers are designed substantially to eliminate clearance between mated couplers, perfect alignment both horizontally and vertically is required between adjacent couplers to be coupled.

A further objection sometimes arises in the use of such tight lock couplers as above referred to in that they are utilized almost exclusively in passenger service where a minimum of noise is desirable, especially on sleeping cars; and the solid metal to metal contact between the tight lock couplers is disadvantageous from this standpoint.

In order to overcome certain of the above-mentioned objectionable features, I have designed a novel form of tight lock coupler, the details of which are hereinafter more clearly set forth.

The general object of my invention is to devise an automatic knuckle type coupler of tight lock design wherein some degree of play will be afforded between locked couplers while, at the same time, all of said play will be under resilient control effective to reduce said play to a minimum while also facilitating ease of manufacture and convenient and facile operation in service.

A different object of my invention is to eliminate the danger of accidental uncoupling in a coupler of tight lock design by utilizing therein a lock with a vertical locking face for engagement with a vertical locking face on the knuckle, in which design pulling stresses will tend to hold the lock in normal locked position, and the anticreep mechanism need function only to guard against such abnormal conditions as bouncing action which may occasionally occur.

Another object of my invention is to devise a tight lock coupler wherein sufficient manufacturing tolerances are permitted to facilitate interchange therebetween and likewise to reduce the cost thereof while, at the same time, affording relative ease of coupling and uncoupling in a coupler wherein all slack will be under resilient control.

My novel form of tight lock coupler contemplates a design wherein the knuckle is permitted to close in slightly from its normal pulling position, thus affording clearance or lead at the back of the knuckle tail and insuring positive dropping of the lock.

My novel form of tight lock coupler also contemplates a design suitable for interlocking or interchange with the present standard tight lock coupler as well as the present standard "E" cou-

pler which is utilized on a great majority of present American railway cars.

My novel form of slack control or tight lock coupler contemplates the use of a plurality of resilient means designed either singly or in combination to restrain the rotative movement of the knuckles of locked couplers or the play between mated couplers, certain of which resilient means may be mounted in the knuckle itself, and others of which may be so positioned in the coupler head as to restrain rotative action of the knuckles of locked couplers, and certain other of said resilient means may be so mounted in the coupler heads as to offer a resilient initial contact between couplers in the act of being coupled whether from angular positions or in line so that the coupling operation may be cushioned and quieted.

Still another object of my invention is to devise an automatic coupler of the type above referred to wherein resilient means will be afforded the buffing surfaces on the coupler head against which the knuckle tail normally strikes in the buffing action, not only to reduce the noise attendant upon such buffing action but also to lessen the possibility of fatigue failures through the buffing wall sometimes caused by repeated hammering blows of the knuckle tail.

My novel automatic coupling arrangement as herein described is readily applicable not only to present standard tight lock designs but also to present standard type "E" designs, the free slack of which may be eliminated by utilization of the features herein described.

In the drawings,

Figure 1 is a top plan view of two coupler heads embodying my invention, the couplers being shown in coupled relation with each other and the shanks of the couplers being cut away as not pertinent to my invention.

Figure 2 is a side elevation of the mated couplers shown in Figure 1, the view being taken from the right as seen in Figure 1.

Figure 3 is a sectional view through the mated couplers shown in Figures 1 and 2, the section being taken substantially in the horizontal plane indicated by the line 3-3 of Figure 2, with the couplers shown under pulling conditions, the knuckle of one coupler being shown in elevation and the other partially sectioned.

Figure 4 is a fragmentary sectional view through one coupler, the section being taken in the transverse vertical planes substantially as indicated by the line 4-4 of Figure 3 and a portion of the guard arm being shown as a half front elevation.

Figure 5 is a fragmentary sectional view taken through the knuckle of one of the couplers, the section being taken substantially in the longitudinal vertical plane indicated by the line 5-5 of Figure 3.

Figure 6 is a further fragmentary sectional view taken through the mated couplers as shown in Figure 3, the section being taken substantially in the longitudinal vertical plane indicated by the line 6-6 of Figure 3.

Figure 7 is a view comparable to that of Figure 3 with the couplers shown under buffing conditions.

Figures 8 and 9 show the detailed form of one of my novel forms of resilient means, Figure 8 being a top plan view thereof, and Figure 9 a view in elevation taken from the bottom as seen in Figure 8.

Figures 10 to 16 inclusive show the detailed

structure of my novel form of lock, Figure 10 being a side elevation thereof, Figure 11 a front elevation, Figure 12 a side elevation taken from the side opposite that of Figure 10, Figure 13 a rear elevation, Figure 14 a top plan, Figure 16 a bottom plan, and Figure 15 a sectional view taken substantially in the transverse horizontal plane indicated by the line 15-15 of Figure 11.

Figures 17 and 18 show my novel form of coupler coupled with a tight lock coupler of the present standard, the views in both cases being fragmentary and comparable to that of Figure 3 and taken in the horizontal planes similar thereto, the view of Figure 17 showing the couplers under pulling conditions and that of Figure 18 showing them under buffing conditions.

Figure 19 shows the contour of my novel form of tight lock coupler superposed upon the contour of the present standard tight lock coupler.

Describing in detail my novel form of coupler structure and referring first to the showing thereof as illustrated in Figures 1 to 7 inclusive, it will be noted that each coupler comprises the usual coupler head generally designated 2 integrally formed with the shank 4, a fragmentary portion only of which is shown. The coupler head comprises the usual guard arm portion 6 and the knuckle 8 which may be pivoted at 16 for automatic action in well-known manner. My novel coupler comprises a cavity or recess formed on the coupler head at the knuckle side thereof and I have designated this portion a knuckle tail pocket 12, said pocket serving to house resilient means more particularly described hereafter. Each coupler head is formed with the usual depending trunnion lug 14 affording pivotal connection as at 16 with the rotor 18, the opposite end of which may have pivotal connection as at 20 with the link 22 which serves as a means of connecting said rotor with the lock generally designated 24 (Figure 3). Integrally formed with the knuckle tail pocket of each coupler head and merging with the side walls of the coupler head are the top and bottom wing-like brackets 26 and 28 merging with the intermediate web 29 extending therebetween, said brackets affording gathering means for the guard arm nose of a mating coupler.

As clearly seen from the side elevation of Figure 2, each guard arm 6 has its maximum depth adjacent the nose which may taper therefrom and accommodates therein top and bottom resilient means 30, 30 conveniently positioned for abutment as at 32 and 34 with the vertical faces formed on the extremities of the guide portions 26 and 28 between which the nose of the guard arm may pass. The said nose of the guard arm may have an arcuate configuration which may seat as at 36 against the resilient member 38 (Figure 8) which may be secured as at 40 in said knuckle tail pocket. The opposite end of the resilient member 38 may project through an opening 42 (Figure 4) in the knuckle tail buffing wall 43 of the coupler head for abutment as at 44 with the tail 46 of the adjacent knuckle.

As shown in Figure 3, the resilient member 38 projects through the opening 42 as may be noted at 48, but in the showing of Figure 3, the couplers are in pulling position and the knuckles are therefore rotated to tight abutment against the lock 24 as may be noted at 50. In contrast, the buffing condition illustrated in Figure 7 shows the member 38 compressed by the knuckle at 46 as already mentioned while a slight clearance between the lock and knuckle is illustrated at 52. It may also

be noted that the opposite end of each resilient member 38 is under slight compression when the couplers are in pulling position as illustrated in Figure 3, said slight compression being apparent from the bulge at 54 adjacent the abutment 36 where said resilient member bears against the nose 56 of the adjacent guard arm. Comparing the showing in Figure 7 where buffing conditions are illustrated, it will be seen that the nose 56 of the guard arm has further compressed the resilient member 38 by the bearing at 36, compression as illustrated in Figure 7 being at maximum and being limited by the abutment at 58, 58 of the respective knuckles with the contour face portions of the adjacent coupler heads. In approaching this condition of maximum buff, resistance is offered not only by the resilient members 38, 38 abutting the noses of the guard arms at 36, 36 in combination with the bearing of the opposite ends of the resilient members 38, 38 against the tails of the adjacent knuckles at 44, 44, but also by the upper and lower resilient means 30, 30 which may bear against the adjacent wing portion as at 32, 34 (Figure 2) as already described. An important additional resistance is offered in the buffing movement by the resilient means 60 which is housed in each knuckle and may be compressed by the knuckle face plate 62 which bears against the contour face of the adjacent coupler head as will be readily apparent, said resilient knuckle being constructed and arranged substantially in accordance with that described in detail in Kayler Patent No. 2,098,207, issued in the United States Patent Office November 2, 1937.

It will thus be seen that the resilient means housed in the knuckles and those housed in the knuckle tail pockets, as well as those housed in the guard arms, offer resistance to the closing movement which occurs immediately prior to the metal abutment which occurs when the buffing movement has reached a maximum as illustrated in Figure 7 where the knuckles have rotated in degree to their maximum position where the knuckle tails seat as at 64 against the buffing wall. With the parts in this position, it should be noted that the noses of the mating knuckles are in full engagement with each other as indicated at 66 and the face of the knuckle is likewise in full engagement at 58 with the throat contour of the adjacent coupler head so that a substantially solid column of metal is afforded from one coupler head to the abutting knuckles into the other coupler head, and this solid metal contact through the two mating couplers is extended through the resilient knuckles thereof as may be seen from a consideration of the view of Figure 5 where metal to metal abutting faces are afforded adjacent the extremities of each face plate as at 65, 65; 67, 67, and an intermediate abutting face at 69.

In this connection, it may be noted that while I have illustrated my novel form of coupler with the resilient means 30, 30 in each guard arm, nevertheless, the said resilient means 30, 30 are not essential to the adequate functioning of my novel form of coupler in which sufficient resilient resistance would be offered in the coupling operation as well as to restrain free slack therebetween if the said resilient means 30, 30 were omitted. When, however, my novel form of coupler is to be coupled with the present standard tight lock coupler, this resilient means is helpful in aligning the couplers, it being understood, of course, that the resilient means 30, 30 will be present at only one side of the mating couplers when my

novel form of coupler is coupled with the present standard tight lock coupler which does not utilize this particular feature. The resilient means 30, 30 being present at one side of the coupler heads as they are approaching each other will tend to rotate them to the position where they are most open with respect to each other so that the knuckles may properly engage and close.

A further comparison may be had between the full buffing conditions illustrated in Figure 7 and the full pulling conditions shown in Figure 3. It will be seen that under pulling conditions each knuckle face plate 62 is still in abutment at 58 with the throat of the opposing coupler head, the knuckle spring 60 being placed under substantial compression in its released position so that, even under conditions of pull, the resilient means in the knuckles offers substantial resistance to longitudinal play between the mated coupler heads and greatly reduces the free slack which otherwise would be present. At the same time, the resilient members 38, 38 are also in some compression as noted at 54 and add to the stability of the coupling arrangement since each resilient member 38 is restrained against movement in its confining pocket.

It should be observed that with the parts in full buffing position as illustrated in Figure 7, the resilient members 38, 38 are compressed at both ends and forces applied thereagainst by the abutting guard arm noses at 36, 36 are transmitted through the resilient members 38, 38 to the knuckle tails at 44, 44 so that each resilient member 38 affords a direct force path from the knuckle tail of one coupler to the guard arm of the mating coupler. This is an important feature of my invention. The tail form of the resilient member 38 is shown in Figures 8 and 9 wherein it may be noted that it is somewhat arcuate in plan with a convex outer surface 68 and a concave inner surface 70 complementary in form to the abutting walls of the pocket within which it may be housed, said member presenting at the outer end thereof a substantially flat face 72 of relatively large area for abutment with the nose portion of the guard arm of a mating coupler and presenting adjacent its opposite end top and bottom shoulders 73, 73 which may abut the marginal edges of the buffing wall 43 around the opening 42 (Figure 3). That portion of the member 38 projecting beyond the shoulders 73, 73 may be of somewhat reduced depth and present an arcuate face 74 having a configuration complementary in form to that of the knuckle tail 46 which may seat thereagainst. After assembly, each resilient member 38 may be held in position by a rivet at 40 and a vertical opening 78 is afforded therefor. It should be noted that all edges of the member 38 are formed with smooth radii as at 76, 76 so that when the member is subjected to compression there will be no tendency for the edges to wear rough or to break down due to concentration of forces transmitted therethrough.

In the sectional view of Figure 4 taken transversely through the coupler in the plane shown in Figure 3, there are illustrated, in addition to features already referred to, certain details not heretofore mentioned. The view of Figure 4 shows the manner in which the lock 24 may ride upon the knuckle as at 80 and 82 and in this view also is shown the knuckle thrower 84 which is the means of rotating the knuckle itself. In this view is also shown the manner in which the rotary lock lifter 18 is connected to the lower

jaw end of the link 22 and the connection of the opposite or eye end of said link to the lifter lug 86 adjacent the lower end of the lock 24. Figure 4 also well illustrates the manner in which the shoulders 73, 73 of the resilient member 38 abut the knuckle tail buffing wall at 88, 88. This view likewise shows a front elevation of the guard arm resilient means 30 which may be described as a generally rectangular body of resilient material with smooth radii at the corners thereof and which may be secured in position by the threaded bolt 90 (Figure 3) fixed to an adjacent transverse web in the guard arm. In this view is also shown the manner in which the lock 24 bears against the vertical longitudinal wall 92 of the coupler head as seen at 94, the bearing surface thereof affording a large seating area for said lock.

The detail of the lock is shown in Figures 10 to 16 inclusive. The general outlines of the lock are similar to those of the present standard tight lock coupler including the relatively large upper portion 96 which may be designated the head of the lock, the guard arm side of which may be afforded a relatively large flat bearing area 98 for the purpose already mentioned, and the opposite face of the lock head may be formed with an offset at 100 defining a shoulder which may seat upon the knuckle tail as already described. The fulcrum 102 may project from the front face of the lock head, said fulcrum affording means about which the lock may pivot against a shoulder provided on the coupler head for that purpose. Also on the knuckle side of the lock head is afforded a relatively large bearing area 104 approximately parallel with the before-mentioned face 98 so that when the knuckle is in pulling position the tail thereof may bear against the area 104, the lock thus being confined between the wall 92 of the coupler head and the knuckle tail, said lock thus serving as means of preventing further rotation of the knuckle in the usual manner. The leg of the lock designated 105 projecting downwardly from the head portion has the intermediate section shown at 106 in Figure 15, said leg portion being somewhat diagonally arranged with respect to the head of the lock. Below the diagonal section 106 the lock has the configuration which may be seen from a comparison of the views of Figures 10, 12, 13 and 16, the lock leg having adjacent the extremity thereof on the guard arm side the lifter lug 86 affording means of connection to the lifter link 22, and above said lug and to the rear thereof may be formed the shoulder 110 on which the lock may rest when in lockset position. Below and forwardly of the lifter lug 86 may be formed the anticreep lug 112 designed to prevent the accidental elevation of said lock when the parts are in locked position. The distinctive feature of my lock as compared with that of the standard tight lock coupler lies in the fact that the knuckle tail bearing area 104 at one side of the lug and the bearing face 98 at the opposite side thereof are substantially parallel with each other so that when the knuckle is in pulling position there is no wedging action which otherwise might tend to urge the lock out of its normal locked position.

In Figures 17 and 18, I have shown my novel form of tight lock coupler connected to the present standard tight lock coupler, Figure 17 showing the couplers in pulling position, and Figure 18 illustrating them in buff. It may be noted that when these two types of couplers are coupled to-

gether and in pulling position the nose 114 of the guard arm 116 of the standard coupler generally designated 117 may abut as at 118 the resilient member 38 of my novel form of coupler, said resilient member being under some compression as a result of said engagement. Also, the knuckle 8 being rotated to its fully open position bears as at 50 against the vertical knuckle locking face of the lock 24, the opposite face of which may seat as at 94 against the vertical wall 92 as already described. The face plate 62 of the knuckle of my novel form of coupler may bear as at 120 against the throat contour of the standard tight lock coupler 117. Also, each resilient member 30 in the guard arm 6 of the coupler head 2 may abut as at 122 the adjacent bracket 124 on the hollow bracket 126 of the coupler 117, said hollow bracket serving to house the nose portion 56 of the guard arm 6. In this view the knuckle 128 of the coupler 117 pivoted as at 130 may have nose engagement as at 131 with the knuckle 8, and the tail of the knuckle 128 may have metal to metal bearing as at 132 against the sloping wedge face of the lock 136, the opposite face of the lock being seated as at 138 against the vertical wall 140 of the coupler head, only a fragmentary portion of said wall being shown. The opposite side of the knuckle tail may be wedged as at 133 against the buffing wall 134 of the coupler head if the wedge lock 136 has descended to the lowermost position permitted by the wear that may have occurred between the engaging surfaces on the buffing wall 134, the knuckle 128, the lock 136, and the wall 140. If for any reason the lock 35 may have wedged upwardly slightly, some clearance will occur at 133. With the parts in pulling position, it will be seen that there is a slight space between the knuckle 128 and the throat contour of the coupler head 2 as indicated at 142, the clearance therebetween being slight and control of the slack resulting therefrom being afforded by the resilient means in the knuckle, by the compression of the resilient member 38, and of the resilient means 30, 30.

In the view of Figure 18 my novel coupler and the standard tight lock coupler are shown coupled and in buffing position. Under these conditions, the resilient members 38 and 30, 30 are considerably further compressed and the knuckle face plate 62 may be forced into metal to metal engagement with the knuckle 8, the spring 60 like the resilient means 30 and 38 being compressed approximately to the maximum and all of said springs cooperating to restrict the amount of metal to metal contact and reduce the resultant noise. The knuckle face plate in its fully compressed position bears as at 120 against the throat of the coupler 117, and the heel of the knuckle 8 may also bear as at 143 against the throat contour of the coupler 117. Also the nose contours of the knuckles 8 and 128 may abut as at 144, while the face of the knuckle 128 may seat as at 146 in the throat contour of the coupler head 2. Under these conditions of buff, the tail of the knuckle 8 has seated as at 64 against the buffing wall 43 and has compressed the inner end of the resilient member 38 into a position flush with the inner face of the wall 43, the knuckle tail bearing against the member 38 as at 44 so that the resilient member 38 affords a direct force path between the nose 114 of the guard arm 116 of the coupler 117 and the tail of the knuckle 8 of the mating coupler 2. With the parts of the respective couplers in buffing position, the tail of

the knuckle 8 may be spaced somewhat from the wall 104 of the lock 24 but the corresponding wedge surface of the knuckle 128 will seat against the wedge face 132 of the wedge lock 136 and, at the same time, bear against the buffing wall 134 as at 133 if the wedge lock 136 is functioning properly.

In Figure 19 is shown in full lines the contour of my novel coupler and superposed thereon is shown in phantom lines the contour of the present A. A. R. standard tight lock coupler. It may be noted that the two contours are identical from the nose of the guard arm 6 into the throat of the coupler head and around the throat to a point adjacent the pivot pin of the knuckle as is indicated at 148 from which point on, the knuckle contour of the A. A. R. tight lock coupler as indicated at 150 is somewhat tighter or closer to the throat of the coupler head than the nose of my novel coupler as indicated at 152, the two knuckle contours crossing each other at a point indicated at 154 and the contour of my novel coupler being modified by the contour of the projecting face plate 62 which normally projects therefrom. From the point 154 around the face of the knuckle, the contour of the standard tight lock coupler is in a somewhat more closed position as compared with the contour of my novel coupler, the two again coinciding at the point designated 156 rearwardly of the heel of the knuckle and approximately opposite the point 148, already mentioned, on the other side of the pivot opening, the center of which may be designated 158. Continuing from the point 156 the two contours again coincide except at the extremities of the brackets formed on the coupler head at the knuckle side thereof wherein it may be noted that said bracket projects slightly farther on the standard tight lock contour as indicated at 160. It will thus be seen that the difference in the two contours is substantially that indicated by the fact that in my novel arrangement the knuckle may open slightly as compared with the knuckle of the standard tight lock coupler, thus permitting more practical manufacturing tolerances, and at the same time, facilitating ease of coupling and uncoupling and also eliminating the hazard of the wedge lock.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a coupling, mating couplers each comprising a pivoted knuckle, a laterally spaced guard arm, a lock presenting substantially vertical walls for compression between said knuckle and an opposing wall on the supporting coupler, said knuckles being capable of limited rotation under locked conditions, and a plurality of resilient means housed in said couplers said resilient means comprising vertically spaced resilient members mounted on each guard arm for abutment with means on the opposite coupler, buffing means resiliently mounted in each knuckle, and a block of resilient material compressible between the knuckle tail of each coupler and the guard arm of the other coupler.

2. In a coupling, mating couplers each comprising a pivoted knuckle, a laterally spaced guard arm, and a lock presenting substantially vertical walls for compression between said

knuckle and an opposing wall on the supporting coupler, said knuckles being capable of limited rotation under locked conditions, and resilient means housed in said couplers said resilient means comprising a resilient member affording a direct force path between the knuckle tail of one coupler and the guard arm of the other coupler.

3. In a coupling, mating couplers each comprising a pivoted knuckle, a laterally spaced guard arm having a nose, a lock presenting substantially vertical walls for compression between said knuckle and an opposing wall on the supporting coupler, said knuckles being capable of limited rotation under locked conditions, and a plurality of resilient means housed in said couplers said resilient means comprising vertically spaced resilient members mounted respectively on each guard arm above and below its nose for abutment with means on the opposite coupler, and a buffing element resiliently mounted in each knuckle.

4. In a coupling, mating couplers each comprising a pivoted knuckle, a laterally spaced guard arm, and a lock presenting substantially vertical walls for compression between said knuckle and an opposing wall on the supporting coupler, said knuckles being capable of limited rotation under locked conditions, and a plurality of resilient means housed in said couplers, said resilient means comprising a plurality of resilient members in each coupler compressible between the knuckle thereof and the throat and guard arm respectively of the adjacent coupler.

5. In a coupling, mating couplers each comprising a pivoted knuckle, a laterally spaced guard arm having a nose, and a lock presenting substantially vertical walls for compression between said knuckle and an opposing wall on the supporting coupler, said knuckles being capable of limited rotation under locked conditions, and a plurality of resilient means housed in said couplers said resilient means comprising vertically spaced resilient members mounted respectively above and below each guard arm nose for abutment with means on the opposite coupler.

6. In a coupling, mating couplers each comprising a pivoted knuckle, a laterally spaced guard arm, and a lock presenting walls for compression between said knuckle and an opposing wall on the supporting coupler, said knuckles being capable of limited rotation under locked conditions, and a plurality of resilient means housed in said couplers, said resilient means comprising a plurality of resilient members in each coupler compressible respectively between the knuckle thereof and longitudinally spaced portions of the adjacent coupler.

7. In a coupling, mating couplers each comprising a pivoted knuckle, a laterally spaced guard arm, and a lock presenting walls for compression between said knuckle and an opposing wall on the supporting coupler, said knuckles being capable of limited rotation under locked conditions, and a plurality of resilient means housed in respective couplers and operative to restrain said rotation, said resilient means comprising a resilient member in each coupler compressible between the knuckle thereof and the guard arm of the adjacent coupler.

8. In an automatic coupler, a pivoted knuckle, a guard arm having a nose laterally spaced from said knuckle, vertically spaced resilient means mounted above and below said nose for cooperation with a portion of a mating coupler, and a

resilient member mounted in the first-mentioned coupler adjacent the tail of said knuckle for abutment therewith, said resilient member projecting from the first-mentioned coupler for abutment with the guard arm of said mating coupler to afford a direct force path between said knuckle tail and said last-mentioned guard arm.

9. In a coupling, mated couplers each comprising a pivoted knuckle and a guard arm laterally spaced therefrom, said arm comprising vertically spaced housing means and an intervening nose, locking means for said knuckles, resilient means housed in said couplers adjacent the tails of said knuckles and compressible between said knuckle tails and the adjacent guard arm noses, and spaced resilient means in respective housing means having abutment with means on the opposite coupler.

10. In a coupling, mated couplers having guard arms and pivoted knuckles laterally spaced therefrom, locking means for said knuckles, and resilient means housed in said couplers adjacent the tails of said knuckles, each of said resilient means affording a direct force path between the tail of a knuckle and the nose of the guard arm of the mating coupler.

11. In a coupling, mated couplers each having a guard arm and a laterally spaced pivoted knuckle, locking means for said knuckles, and resilient means housed in said couplers adjacent the tails of said knuckles, each of said resilient means affording a direct force path between the knuckle tail of one coupler and the guard arm of the other coupler.

12. In an automatic coupler, a pivoted knuckle, a guard arm having a nose laterally spaced from said knuckle, vertically spaced resilient means mounted in said arm above and below said nose for abutment with a mating coupler, and a resilient member mounted in said first-mentioned coupler adjacent the tail of said knuckle for abutment therewith, said resilient member projecting from the first-mentioned coupler for abutment with the guard arm of said mating coupler.

13. In an automatic coupler, a pivoted knuckle, a guard arm having a nose laterally spaced from said knuckle, vertically spaced resilient means mounted in said guard arm above and below said nose and having abutment with a portion of a mating coupler, a resilient member mounted in said coupler adjacent the tail of said knuckle for abutment therewith, and means resiliently mounted in said knuckle for abutment with the throat of a mating coupler.

14. In a coupling, couplers each having a guard arm and a laterally spaced pivoted knuckle, locking means for said knuckles, and resilient means mounted in at least one of said couplers and affording a direct force path between the knuckle thereof and the guard arm of the mating coupler.

15. In a coupling, couplers having guard arms and pivoted knuckles laterally spaced from said arms, locking means for said knuckles, and resilient means in said couplers, each of said resilient means affording a direct force path between the knuckle tail of one coupler and the guard arm of the other coupler.

16. In a coupling, mated couplers each comprising a pivoted knuckle and a guard arm laterally spaced therefrom, locking means for said knuckles, and resilient means housed in each coupler adjacent the tail of said knuckle and

compressible between a portion of said knuckle and the guard arm of the mating coupler.

17. In a coupler, a coupler head, a knuckle pivoted therein and comprising a tail portion, locking means for said knuckle, and resilient means adapted to afford a direct force path to said tail portion from a portion of a mating coupler.

18. In a coupler, a coupler head, a knuckle pivoted therein and comprising a tail portion, locking means for said knuckle, and resilient means carried by said coupler head and compressed at all times by a portion of a mating coupler, said resilient means being further compressible under certain operating conditions by said knuckle tail portion.

19. In a coupler, a coupler head, a knuckle pivoted therein, locking means for said knuckle, and a plurality of resilient means housed in said coupler, said resilient means comprising a plurality of resilient members compressible between said knuckle and the throat and guard arm respectively of a mating coupler.

20. In a coupler, a coupler head, a knuckle pivoted therein, locking means for said knuckle, and a plurality of resilient means housed in said coupler and compressible respectively between said knuckle and longitudinally spaced portions of a mating coupler.

21. In a coupler, a coupler head, a knuckle pivoted therein and having a tail portion, and cushioning means compressible between said tail portion and a portion of a mating coupler.

22. In a coupler, a pivoted knuckle, and cushioning means mounted in said coupler adjacent the tail of said knuckle for abutment therewith, said coupler having a wall with rigid abutment means for engagement with said tail under maximum buffing conditions to prevent overcompression of said cushioning means and to positively limit rotation of said knuckle under said conditions, and said cushioning means extending outwardly through an opening in said wall for engagement with an associated mating coupler.

23. In a coupler, a coupler head, a knuckle pivoted therein, said knuckle comprising a tail portion, said head comprising a knuckle tail buffering wall adjacent said tail portion, an opening through said wall, and cushioning means projecting through said opening for engagement with said tail portion under certain operating conditions, said cushioning means being in the form of an arcuate resilient pad extending outwardly through said opening for engagement with a mating coupler.

24. In a coupler, a coupler head, a knuckle pivoted therein, said knuckle comprising a tail portion, said head comprising a knuckle tail buffering wall adjacent said tail portion, an opening through said wall, and cushioning means projecting through said opening for engagement with said tail portion under certain operating conditions, said cushioning means projecting outwardly of said wall for cooperation with a portion of a mating coupler.

25. In a coupler, a coupler head, a knuckle pivoted therein, said knuckle comprising a tail portion, said head comprising a guard arm pocket and a knuckle tail buffering wall adjacent said tail portion, an opening through said wall, and cushioning means in said pocket and projecting through said opening for engagement with said tail portion.

26. In a coupler, a coupler head with a cavity,

a knuckle pivoted therein and having a tail portion, and cushioning means within said head and projecting outwardly of said cavity for engagement with a mating coupler, said cushioning means being normally spaced from said portion during locked position of the knuckle and said cushioning means being engageable with said portion under buffing conditions only.

27. In a coupler, a coupler head, a knuckle pivoted therein and having a tail portion, and cushioning means within said head and projecting outwardly through a wall of said head for engagement with a mating coupler, said cushioning means being normally spaced from said portion during locked position of the knuckle and said cushioning means being engageable with said portion under buffing conditions only, said head being formed with knuckle tail buffing means for engagement with said tail portion to limit compression of said cushioning means and to positively limit rotation of said knuckle during maximum buffing conditions. 20

28. In a coupler, a coupler head comprising a guard arm having a guard arm nose, and spaced cushioning means mounted on said arm above and below said nose respectively for cooperation with a mating coupler.

29. In a coupling, mated couplers each having a knuckle pivoted therein and comprising resilient buffing means bearing against the other coupler, said knuckle having a tail portion, and cushioning means within each head for cooperation under buffing conditions only with the associated tail portion, said buffing means being operable to maintain said tail portion out of engagement with said cushioning means under normal conditions. 10

30. In a coupler, a pivoted knuckle with a tail portion, and cushioning means formed and arranged to afford a direct force path between said portion and a mating coupler. 15
